(57) **CLAIM**

The ornamental design for a construction toy piece, as shown and described.

DESCRIPTION

FIG. 1 is a front elevation view of the construction toy piece. FIG. 2 is a back elevation view of the construction toy piece. FIG. 3 is a top elevation view of the construction toy piece. FIG. 4 is a bottom elevation view of the construction toy piece.

FIG. 5 is a right elevation view of the construction toy piece. FIG. 6 is a left elevation view of the construction toy piece; and,

FIG. 7 is a top front right isometric view of the construction toy piece.

The broken lines in the figures depict portions of the construction toy piece that form no part of the claimed design.
